UNITED STATES PATENT OFFICE.

CARL C. RIOTTE, OF NEW YORK, N. Y., ASSIGNOR TO THE C. C. RIOTTE COMPANY, OF NEW YORK.

DESIGN FOR A CASING FOR GAS-ENGINES.

SPECIFICATION forming part of Design No. 30,279, dated February 28, 1899.

Application filed January 26, 1899. Serial No. 703,511. Term of patent 14 years.

To all whom it may concern:

Be it known that I, CARL C. RIOTTE, a citizen of the United States, residing at New York, county of New York, State of New York, have invented and produced a certain new, useful, and original Design for a Gas-Engine Casing, of which the following is a full, clear, and exact description.

My invention relates to a new and original design for a gas-engine casing.

In the accompanying drawings, Figure 1 is a front elevation of a casing for a gas-engine. Fig. 2 is an end elevation of the same. Fig. 3 is a plan view.

A is a substantially flat head-piece or cap having when viewed in plan substantially parallel sides terminating in rounded ends. Below this head-piece and merging thereinto is a body B, of an external outline corresponding substantially to the outline of the before-referred-to part A.

C are cylindrical extensions from the under side of the body B, said parts C appearing as spaced apart and substantially parallel with each other. The parts C are seen to merge into the substantially flat top of the lower body D, the ends of which are substantially vertical, while the opposite sides of

which, as shown in Fig. 2, incline quite substantially toward each other.

E is a shoulder extending from the body D in a plane considerably above the bottom of said body, which, as shown, is rounded.

Subordinate to the above features is a dished end extension F.

G G are ribs which are located just below shoulder E and which when viewed in front elevation, Fig. 1, appear to be in parallel vertical arrangement.

H is a somewhat inconspicuous projection from one of the flat faces of the body B and in the upper central portion of the same.

The leading or characteristic features of the design herein reside in the compact and graceful form of the casing as a whole and in the generally unitary effect of the upright body portion of the same.

What I claim is—

The design for a casing for a gas-engine substantially as herein shown and described.

Signed at New York, N. Y., this 21st day of December, 1898.

CARL C. RIOTTE.
